United States Patent Office

Des. 176,263
Patented Dec. 6, 1955

176,263

MOTORCYCLE

Tadashi Ito, Shinjuku-Ku, Tokyo, Japan

Application September 20, 1954, Serial No. 32,356

Term of patent 14 years

(Cl. D90—8)

Fig. 1.

Fig. 2.

Fig. 3.

Fig. 5.

Fig. 4.

In the drawings:

Fig. 1 is a side elevational view of a motorcycle, showing my new design.

Fig. 2 is a side view looking from the back side of Figure 1.

Fig. 3 is a top plan view of Figure 1.

Fig. 4 is a front view looking from the right end of Figure 1.

Fig. 5 is a rear view looking from the left end of Figure 1.

I claim:

The ornamental design for a motorcycle, substantially as shown.
